UNITED STATES PATENT OFFICE.

EDSON R. WOLCOTT, OF LOS ANGELES, CALIFORNIA, ASSIGNOR, BY MESNE ASSIGNMENTS, TO THE TEXAS COMPANY, OF NEW YORK, N. Y., A CORPORATION OF DELAWARE.

TREATING HYDROCARBON OILS.

Application filed October 1, 1924. Serial No. 740,905.

This invention relates to the conversion of higher boiling hydrocarbons into lower boiling ones and has in view particularly the production of gasoline and other similar products.

Broadly and generally my invention contemplates a method of treatment in which the oil is subjected to the disruptive action produced by an explosion or combustion of a rapidly burning material. In practicing the invention the oil to be converted is charged into a confined space and a suitable combustible material contiguous or in close proximity to the oil is fired whereby the oil is subjected to high pressure and heat sufficient to effect molecular decomposition.

In present methods of cracking it is necessary to subject the oil to cracking temperatures and pressures for prolonged periods of time in order to produce the desired decomposition. In accordance with my invention the oil is subjected to sudden explosion with minimum heating thereby avoiding the production of excess quantities of carbon or coke and permanent gas. In the preferred method of carrying out the invention the oil is subjected to extremely high pressure produced by the rapid burning or explosion of a suitable combustible gas for a comparatively short time, for example momentarily, and the resultant products are then suddenly expanded. In one method of practicing the invention a suitable combustible material, such as hydrocarbon gas, is introduced into a combustion chamber provided with a spark plug or other suitable means for ignition. An oil chamber is disposed adjacent the combustion chamber and the oil is retained in the oil chamber by means of frangible partitions formed of thin metal, oil paper or other similar material. The force of the explosion or rapid combustion disrupts the partitions and the heated combustion products are forced into violent contact with the oil, subjecting it to high pressure and completing molecular decomposition. It is preferable to operate continuously, means being provided for introducing new partitions or closures after each explosion. Thus after the oil has been passed into the confined space the combustible material is ignited, the explosion follows and the oil is projected into an expansion chamber. The means for feeding the partitions, the means for ignit-

ing the combustible material and the feed of oil is preferably synchronized so that the operation may be carried on in a continuous manner.

The accompanying drawing is a diagrammatic elevation of an apparatus constituting a preferred embodiment of the invention. By referring to the drawing it will be seen that an expansion or distillation chamber 10 is provided in which are mounted a plurality of U tubes 11. For introducing the oil to be converted a pump 12 and charging line 13 having a plurality of branch lines 14 which lead to the several U tubes, is provided. Each branch line 14 is equipped with a check valve 15. Associated with each U tube is a combustion chamber 16 provided with a spark plug 17 or suitable ignition means. The spark plugs are in circuit with a suitable source of electrical energy and it is preferable to provide interrupters or timing means for controlling the ignition in the several combustion chambers. Each combustion chamber is equipped with a pipe 18 adapted for supplying a suitable combustible fluid, such as a hydrocarbon gas. Means is also provided for admitting air to the combustion chamber or, if desired, the proper explosive mixture of air or gas may be admitted through the pipe 18.

The oil chambers 11 may be provided with restricted outlets 19 in order to assist in obtaining the desired high pressure in the treating chambers. In the apparatus shown the expansion chamber 10 also constitutes a distilling chamber and is provided with a vapor line 20 leading to a suitable fractionating or preliminary condensing means 21, having a liquid or condensate line 22 and a vapor line 23 which terminates in a condenser coil 24. A receiver 25 is provided for collecting the condensate obtained from the condenser 24. The still 10 may be provided with a draw-off line 26.

In practicing the invention with the apparatus shown the oil is introduced into the several U chambers 11. The oil may be fed continuously or suitable timing mechanism, working synchronously with the timing mechanism for the ignition means 17, may be provided to control the flow. When the explosion or rapid burning occurs in a given combustion chamber 16 the products of combustion are forced violently in contact with

the oil in the pipe or chamber 11 thereby subjecting the oil to extremely high pressure and a temperature sufficient to produce decomposition. The oil is then expanded by 5 being forced through the restricted outlet into the chamber 10. The vaporizing products are taken off through the vapor line 20 into the fractionating means 21 wherein certain lower boiling point products are 10 condensed. These products are drawn off through the pipe 21 and may be utilized as desired. The vapors passing from the separator or fractionating means 21 are passed to the condenser coil 24 and the gasoline or 15 other volatile product desired is collected as a condensate in the receiver 25.

It is apparent that various methods of operation and types of apparatus may be employed in the practice of the invention. One 20 advantageous method is to feed the oil to the combustion or treating chamber through a porous medium. Thus a cylindrical treating chamber may be provided having about its internal periphery an annular mass of porous material onto which the oil to be converted is fed. The combustible gas is fired in the interior of the chamber and thus operates upon the oil feeding through the porous material.

30 Although the preferred embodiment of the invention has been set forth in connection with apparatus having a particular construction and arrangement of parts and mode of operation, it is obvious that various changes 35 and modifications may be made therein, while securing to a greater or less extent some or all of the benefits of the invention,

without departing from the spirit and scope thereof. Therefore, only such limitations should be imposed as are indicated in the 40 appended claims.

What I claim is:

1. The process of converting higher boiling hydrocarbons into lower boiling ones that comprises introducing a combustible mixture and a quantity of oil into a chamber, firing said mixture under pressure to momentarily subject the oil to a cracking temperature under high pressure and then subjecting the oil to expansion to effect distillation thereof. 45

2. The process of converting higher boiling hydrocarbons into lower boiling ones that comprises introducing a quantity of liquid oil into a chamber, exploding gas under compression contiguous to said body of oil to momentarily subject said oil to a cracking temperature under superatmospheric pressure to cause the formation of lower boiling hydrocarbons and then discharging the converted oil from said confined space. 55

3. The process of converting higher boiling hydrocarbons into lower boiling ones that comprises introducing the oil to be treated into a plurality of pools, exploding gas under compression in a plurality of pockets contiguous to said pools to momentarily subject the several pools of oil to cracking temperatures under superatmospheric pressures and discharging the resultant products into an enlarged chamber. 65 70

In witness whereof I have hereunto set my hand this 10th day of September, 1924.

EDSON R. WOLCOTT.
